CLAIM

The ornamental design for a light-emitting diode vehicle mount, as shown and described.

DESCRIPTION

FIG. 1 is a front perspective view of a light-emitting diode vehicle mount, showing my design;

FIG. 2 is a rear perspective view of FIG. 1;

FIG. 3 is a right side perspective of FIG. 1;

FIG. 4 is a left side perspective view of FIG. 1;

FIG. 5 is a front elevation view of FIG. 1;

FIG. 6 is a rear elevation view of FIG. 1;

FIG. 7 is a right side elevation view of FIG. 1 at an increased scale;

FIG. 8 is a left side elevation view of FIG. 1 at an increased scale;

FIG. 9 is a top plan view of FIG. 1; and,

FIG. 10 is a bottom plan view of FIG. 1.
